UNITED STATES PATENT OFFICE.

ERNEST ROWLAND HILL, OF EAST ORANGE, NEW JERSEY, ASSIGNOR TO THE WESTINGHOUSE AIR BRAKE COMPANY, OF PITTSBURGH, PENNSYLVANIA, A CORPORATION OF PENNSYLVANIA.

TRIP-VALVE DEVICE FOR AIR-BRAKES.

1,133,645.

Specification of Letters Patent. Patented Mar. 30, 1915.

Application filed May 10, 1911. Serial No. 626,322.

To all whom it may concern:

Be it known that I, ERNEST ROWLAND HILL, a citizen of the United States, residing at East Orange, in the county of Essex and State of New Jersey, have invented new and useful Improvements in Trip-Valve Devices for Air-Brakes, of which the following is a specification.

This invention relates to trip valve devices for air brakes adapted to be operated by a trip mechanism located along the track and connected with the signal system whereby the trip valve device is actuated to vent air from the train brake pipe to apply brakes in case the train runs past a signal set at danger.

The principal object of my invention is to provide an improved valve device of this character wherein a small auxiliary or pilot valve is actuated directly by the trip mechanism and operates to vary the pressure on a movable abutment or piston for causing the opening of the main vent valve.

Another object is to provide improved means, in a valve device of this type, for holding the vent valve open a certain length of time or until the train pipe pressure has reduced to a given low degree.

These and other features of my improvement will hereinafter more fully appear from the following description and be set forth in the claims.

In the accompanying drawings: Figure 1 is a vertical sectional view of one form of trip valve device embodying my improvement; and Fig. 2 is a similar view, showing a slightly modified construction.

According to the construction shown in both figures, the stem, 15, is adapted to be actuated by any suitable or preferred form of trip device located along the track in connection with a signal system or otherwise, and operates the small pilot or auxiliary valve, 14, which controls the pressure acting on the main piston or abutment, 11, connected to the main vent valve, 10, which controls the escape of air from the train pipe line, 8, to the atmosphere.

The auxiliary valve may be arranged to control the supply of air under pressure from the train line to the main piston, 11, for actuating the same to open the vent valve, 10, as shown in Fig. 1, or the main

piston may be normally exposed to train pipe pressure on both sides and the auxiliary valve arranged to release the air under pressure from one side of said piston whereby the pressure on the other side operates to move the piston and open the main vent valve, 10, as shown in Fig. 2. In this latter form of construction the valve chamber, 7, on one side of piston, 11, is in open communication with the train line, 8, and the piston is loosely fitted or has a small hole through it so as to permit the pressure to equalize around into the chamber, 12, on the opposite side, the spring, 13, being provided to normally move the piston to close the valve, 10, or hold it closed when the air pressure upon opposite sides of the piston is substantially equalized. If the valve, 10, is of the puppet type, as shown, the pressure on the back of the valve also assists in holding the same closed, although it will be understood that a slide valve or any other type may be employed if preferred.

A spring, 17, may be employed for cushioning the movement of the stem, 15, and as shown in Figs. 1 and 2, this spring also acts upon the auxiliary valve and tends to hold same closed or to return said valve to closed position after being opened.

A suitable form of latch mechanism may be provided for locking the stem, 15, in its raised or open position for a predetermined time, or until the train pipe pressure has reduced to a certain degree, such as shown in Figs. 1 and 2, in which the latch, 24, is arranged to engage a collar or groove, 19, on the stem, 15, and is connected to a movable abutment, 20, which is subject to the train pipe pressure on one side and a spring, 22, on the other side, so that when the train pipe pressure reduces to a certain degree the spring, 22, will move the latch to release the stem, 15, and permit the spring, 17, to return same to normal closed position.

As shown in Fig. 1, the spring, 13, normally holds the main valve, 10, on its seat and the auxiliary or pilot valve, 14, is seated on the main valve. When the stem, 15, is raised by the track trip mechanism, the small valve is raised from its seat and air from the train line flows through the hollow stem to the cylinder at the lower face of piston, 11, causing the same to move up

and open the main valve, 10, thereby venting a large volume of air from the train line through the hollow stem, beneath the piston, 11, and out through the exhaust opening, 26, to the atmosphere. The air under pressure acting on the piston, 11, maintains the same in its raised position with the spring, 13, compressed and the main valve fully open until the train pipe pressure had diminished to such a point that the latch, 24, releases the stem, 15, as before explained. The spring, 17, then seats the valve, 14, and assists the spring, 13, in closing the main vent valve, 10.

15 According to the construction illustrated in Fig. 2, the latch 24, is connected to the stem, 23, of the abutment, 20, by means of a spring, 25, so that the latch may readily yield to allow the upward movement of the stem, 15, and collar, 19, without the necessity of moving the abutment, 20, against the opposing air pressure. The latch then instantly springs out beneath the collar, 19, and holds the stem raised with valve, 14, open. As the pressure is thus released from the outer side of piston, 11, through exhaust port, 18, the piston moves over and opens the vent valve, 10; thereby venting a large volume of air from the train pipe, 8, to the exhaust pipe, 9, and the atmosphere. When the train pipe pressure, which acts upon abutment, 20, in chamber, 21, has diminished to a point sufficient to be overcome by the spring, 22, the latter moves the piston, 20, over and withdraws the latch, 24, to permit the spring, 17, to return the auxiliary valve, 14, to its seat. The pressure then equalizes around the piston 11, and the spring, 13, moves the same to close the vent valve, 10, as before described.

40 Having now described my invention,

what I claim as new, and desire to secure by Letters Patent, is:

1. In a trip valve device for air brakes, the combination with a main vent valve, and a fluid pressure actuated piston for operating said valve, of a pilot or auxiliary valve for controlling the pressure on the piston, a stem for actuating the pilot valve adapted to coöperate with a track mechanism, and a latch mechanism for said stem governed by train pipe pressure to hold the pilot valve open until the train pipe pressure has reduced a given amount.

2. In a trip valve device for air brakes, the combination with a main vent valve and piston for actuating same, said piston being subject to fluid pressure upon both sides, of a pilot valve for controlling the release of fluid under pressure from one side of said piston, a stem for actuating the pilot valve and adapted to coöperate with a track mechanism, and a latch mechanism governed by train pipe pressure to hold the pilot valve open until the train pipe pressure is reduced to a predetermined point.

3. In a trip valve device for air brakes, the combination with a main vent valve, and a fluid pressure actuated piston for operating said valve, of a pilot valve for controlling the pressure acting on said piston, a stem for operating said pilot valve, a latch for locking said stem, and a movable abutment subject to train pipe pressure for releasing said latch, the latch having a yielding movement independent of the abutment.

In testimony whereof I have hereunto set my hand:

ERNEST ROWLAND HILL.
